CYLINDER GRINDING TOOL

Wallace F. Mitchell, Chicago, Ill., assignor to Automotive Maintenance Machinery Co., Chicago, Ill., a corporation of Illinois

Application October 14, 1943, Serial No. 506,210

18 Claims. (Cl. 51—184.3)

My invention relates generally to tools adapted for the grinding of the bores of engine, pump and other cylinders either in factory production work or in the reconditioning of worn cylinders, and it has to do particularly with tools of the foregoing character embodying expansible and contractible abrading stones.

One of the objects of my invention is to provide an improved tool of the foregoing character which is of simple and rugged construction, is economical to manufacture, is adapted to grind cylinders and the like to accurate dimensions quickly and with a minimum of power and effort, and which is adapted to perform its cylinder grinding functions in a more efficient manner than prior devices.

Another object is to provide a cylinder grinding tool adapted to provide a fast and smooth cutting action during the grinding operation without chatter and with a minimum of grinding stone wear.

A further object is to provide a tool of the foregoing character which is provided with means for automatically expanding the abrading stones against the cylinder wall in such a manner as to maintain the abrading surfaces of such stones in a clean, non-clogged and non-glazed condition during the grinding operation, so that such abrading stones are adapted to exert their maximum cutting or grinding action during the grinding operation.

Still another object is to provide a cylinder grinding tool having expansible abrading stones, the arrangement being such that a substantially uniform and highly effective grinding action is accomplished even though the grit and grades of the stones employed may vary. Heretofore it has been necessary, in an attempt to arrive at an efficient grinding action for any particular tool, to carefully select the abrading stones so as to substantially match them in respect to the grit and grade thereof. According to my invention, the abrading stones may be engaged with the cylinder wall under variable pressures, which pressures in any particular tool are sufficient to accommodate a wide range of stone grading. For example, soft stones, which require a low pressure in the grinding operation may be employed by use of the desired grinding pressure as determined by the expanding adjustment of the tool, or harder stones which require a greater grinding pressure may be employed by adjusting the same expanding means to apply a greater grinding pressure, all of which may be accomplished without affecting the expansion range of

the expanding means of the tool. Furthermore, in accordance with my invention, the foregoing adjustment features are accomplished with a fast and smooth cutting operation which is devoid of chatter and which is carried out with a minimum of stone wear.

5 A further object is to provide abrasive expanding means for a cylinder grinding tool which is of compressible form having one part with a low deflection and a high frequency characteristic and another part with a high deflection and a low frequency characteristic.

10 A more specific object is to provide abrasive expanding means for a tool of the foregoing character which takes the form of a pair of springs of substantially equal load carrying capacity, one of which has a high rate of vibration and the other of which has a low rate of vibration, the springs being so arranged that the high rate spring is compressed and held compressed during the grinding operation by the low rate spring, whereby the high rate spring is effective for transmitting cutting vibrations to the cutting stones throughout the range of any particular 15 tool adjustment as determined by the extent of compression of the low rate spring.

20 An additional object is to provide spring expanding means of the foregoing character wherein the springs are so related as to insure at all 25 times during the grinding operation the high frequency action of the high frequency spring to maintain the grinding surface of the abrading stones in a clean, full-cutting condition and in such rhythm as to prevent chatter.

25 Still another object is to provide an improved means for automatically limiting the extent of automatic expansion of the tool during any particular grinding operation.

30 Other objects and advantages will become apparent as this description progresses and by reference to the drawing wherein—

35 Figure 1 is an elevational view, partially in section, of one form of cylinder grinding tool embodying my invention;

40 Fig. 2 is a section taken substantially on line 2—2 of Fig. 1;

45 Fig. 3 is a bottom plan view partially in section; and

50 Fig. 4 is a fragmentary elevational view illustrating the means by which the tool is manually adjusted.

55 Referring to the drawing, the tool embodying my invention is well adapted for the grinding of a cylinder 10. Such tool is of the so-called rigid cage-frame type comprising a pair of end plates

11 and 12 rigidly joined together by a plurality of circumferentially disposed and spaced posts 13. The posts 13 provide, in effect, a plurality of radial passageways for receiving abrasive carriers 14 having rectangularly-shaped body portions 14^a, the opposite ends of which are adapted to be slidably received in radial grooves 15 and 16 formed in the confronting faces of the end plates 11 and 12. The outer edges of the abrasive carriers 14 are provided with channeled head portions 17 adapted to receive abrasive stones 18, such stones being secured in place within the channel of the abrasive carrier head by clamp blocks 19. The particular tool shown in the drawing employs four abrasive carriers 14, two of which carriers support abrading stones 18, and the other two support felt guide members 20 which are employed for a purpose well understood in this art.

The tool shown is of the expandable, contractible type, expansion of the carriers 14 being accomplished by an adjustable floating cone unit. This cone unit comprises a threaded stem 21 which extends along the axis of the tool and is of sufficient length to project its lower end through an opening 22 in the lower end plate 12 and through and beyond a universal drive head 23 formed exteriorly on the upper end plate 11. The stem 21 supports a pair of unidirectional cone members 24, 25, the conical surfaces of which engage complementally shaped surfaces 14^b formed along the inner edges of the carrier bodies 14^a. The cones 24, 25 are provided with peripheral notches 27 that receive a post 26 carried by the end plates 11 and 12 whereby the cones are permitted to shift axially of the tool without rotation thereof relative to the tool body. With this arrangement, rotation of the stem 21 relative to the cones 24, 25 causes such cones to shift axially along the carrier surfaces 14^b to expand and contract the latter. The carriers are retained yieldably in engagement with the cones 24 and 25 by garter-like springs 28 and 29 seated in notches formed in the outer edge of the end portions of the carriers adjacent the carrier supporting grooves 15 and 16. These springs 28, 29 are also effective to contract the carriers 14 upon contraction adjustment of the stem 21 and cones 24, 25.

The stem 21 is also free for axial shift movement under the control of spring means. This shift movement of the stem 21 also bodily shifts the cones 24, 25 to expand the carriers 14 and stones 18 against the cylinder wall. To this end, I provide an enlarged axial opening 30 in the universal drive head 23 through which axially passes the upper end of the stem 21. The spring means for moving the cone unit is located in the opening 30 and takes the form of a comparatively thin, washer-type spring 31, cupped or dished as indicated in Fig. 1. The edge of the spring 31 in the form shown seats upon the bottom of the opening 30, which bottom surface is preferably hardened to prevent the edge of the spring from digging in and causing the same to become paralyzed and inoperative. If desired, a hardened washer (not shown) may be inserted under the spring to accomplish the same purpose. The spring 31 is of predetermined load carrying capacity, has a small deflection characteristic and has a high rate of vibration. Upon the spring 31 there is mounted a coil spring 32 having substantially the same load carrying capacity as the spring 31, but a high deflection characteristic and a comparatively low rate of vibration. The

spring 31 is seated upon the bottom of the opening 30 and both springs surround the upper end of the stem 21, being confined as a unit between the bottom of the opening 30 and a depending skirt-like portion 33 of a knurled adjusting knob 34. The skirt-like portion 33 of the adjusting knob is secured to the stem 21 by a pin 35 or like means.

In the use of the foregoing structure, the tool is first contracted by rotating the adjusting nut 34 and stem 21 in a left-hand or counterclockwise direction. In this operation the stem 21 rotates without axial shift movement while the cones 24, 25 are shifted along the stem in carrier contracting direction. The tool is then placed in the cylinder 10 to be ground, after which the adjusting nut 34 is turned in a right-hand or clockwise direction to expand the tool to an extent to bring the abrasive stones 18 and felts 20 into firm engagement with the cylinder wall. In this operation, the cones 24, 25 only are shifted axially by movement along the stem 21. However, in finally adjusting the tool to compress the springs 31, 32 for automatic tool expanding and grinding operation, a different action takes place. In further rotation of the adjusting knob 34 and stem 21, after the stones have engaged the cylinder wall, the cones 24, 25 remain stationary while the stem 21 shifts axially downward to compress the springs 31, 32. The extent of rotation of the knob 34 and the stem 21 depends upon the amount of material to be removed from the cylinder wall. After this final adjustment is made, the spring unit 31, 32 constantly urges the stem 21 upward tending to move the cones 24, 25 in the same direction to automatically expand the carriers 14. As the tool is rotated and material is removed from the cylinder wall the tool is gradually expanded under the influence of the spring unit.

As the foregoing final adjustment was made, the lower end 21^a of the stem 21 carrying a stop block 36 moved downwardly away from the enlarged part 22^a of the opening 22 in the lower end plate 12. As the tool is automatically expanded by the spring unit 31, 32, the stop block 36 moves upwardly toward the end plate 12, and when it engages the bottom of the opening 22^a no further adjustment can take place by the springs 31, 32. Thusly, the lower end of the stem and the stop block 36 are utilized as adjustment limiting means, and the extent to which the tool may be expanded under the control of spring expanding means is determined by the extent of rotation of the stem 21 after the stones engage the cylinder wall and the distance that the stop block 36 moves downwardly away from the bottom end plate 12.

It will be recognized by those skilled in the art that one may determine with a fair degree of accuracy the amount of material that will be removed from the cylinder wall with any particular adjustment. For example, one may readily determine the extent to which the adjusting knob 34 need be turned in a particular tool for removal of a certain amount of material for the cylinder wall, and to facilitate accuracy in use of the tool I have provided an indicator by which the operator may determine the extent to which the tool has been adjusted and in turn the amount of material that may be removed from the cylinder wall. To this end I have provided immediately beneath the adjusting knob 34 a rotatable sleeve 37 having at its upper edge a somewhat enlarged peripheral

knurled bead 38 which may be readily grasped for turning the same. The sleeve 37 is rotatably confined between a lock ring 39 on the adjusting knob skirt 33 and the underside of the adjusting knob, a disk-like spring 40 being disposed between the knob 34 and the sleeve 37 to permit relative rotation of the sleeve and the knob when so desired but to otherwise cause the two to rotate together. The sleeve 37 is provided with a calibrated scale which registers with a suitable indicating mark 23^a exteriorly visible on the universal drive head 23. In this use of this structure, after the abrading stones 18 have been set up initially against the cylinder wall and before final adjustment is made to compress the springs 31, 32, the sleeve 37 is rotated to bring its zero mark in line with the indicating mark 23^a on the head 23. The adjusting knob 34 is then rotated as above explained, carrying the sleeve with it, the distance that the zero mark of the sleeve moves away from the indicating mark on the head 23 indicating the extent to which the tool has been adjusted for the grinding operation and indicating the extent to which material will be removed from the cylinder wall before the adjustment limiting block 36 becomes effective to stop further adjustment of the tool.

The tool may be driven by any suitable power means such as an electric drill or the like. To adapt it for driving, I preferably employ a universal coupling sleeve 41 adapted to operably engage pins 42 on the universal drive head 23, which sleeve is pivotally carried by a yoke-like member 43 to which is rigidly secured a driving spindle 44. This spindle may be connected directly to the power means which may be such as to merely rotate the tool or both rotate and reciprocate the same.

The construction and operation of my invention will, I believe, be understood from the foregoing description. Thorough demonstration has shown that in the use of a tool embodying my invention the grinding operation is carried out smoothly and without chatter; it is carried out much more rapidly than in any known prior tool, and abrading stone wear is reduced to the practical minimum. I have found by demonstration, operating the tool in the manner of prior tools, that I am able to remove .005" of material from the cylinder wall in approximately one minute, or more than twice as fast as prior tools. Demonstration has further shown that this amount of material may, with my invention, be removed without any appreciable wear on the grinding stones and throughout the operation the tool does its work with a smooth non-chatter action. From my analyses of the tool in operation and otherwise, I believe that these outstanding results, which have long been sought but heretofore unachieved, are due in part at least to the novel spring expanding means employed in carrying out my invention.

A thin washer-type of spring, such as the spring 31, when under compression, furnishes fast or high-speed vibrations, that is, a natural period of vibration of high frequency, which keep the abrading stones in substantially continuous contact with the cylinder wall. This high speed vibration, however, is such that the surface of the abrading stone through its rapid vibrating contact with the cylinder wall is constantly kept substantially clean at all times so that the full intended cutting effect of the

abrading stone is effective upon the cylinder wall surface being ground. With this high speed vibration the abrading stone surface is constantly unloaded and the stones do not become clogged or glazed.

A flat washer-type spring has a total movement from a free length condition to compressed length condition of only a few thousandths of an inch so that it would be necessary, in the use of such spring without other compensating means, to frequently adjust the tool when removing any appreciable amount of material from the cylinder wall. Such adjustment would require frequent stoppage of the tool, slowing up the operation considerably. In carrying out my invention, I eliminate the foregoing disadvantage of the high rate spring by the use of the slow or low speed (low rate of vibration) spring such as the coil spring 32. The coil type of spring 32, as is well known, furnishes slow or low-speed vibrations, that is, a natural period of vibration of low frequency, and, if used alone, would tend to cause the abrading stones to bounce, so to speak, against the cylinder wall so that chattering would take place. This would also tend to cause the stones to break down and wear out quickly, in addition to slowing up the grinding operation due to the out-of-contact period of the abrading stones with the cylinder wall. However, when this low rate spring (like 32) is used with a high rate spring (like 31), all of the foregoing objectionable conditions disappear and new and novel results are obtained. In the claims, I have referred to the washer-type spring as a high frequency spring and the coil spring as a low frequency spring.

In carrying out my invention I have coordinated the low-speed and high-speed springs in such a way as to secure the advantages of both without the defects of either. These springs are preferably of the same load capacity. When the coil spring 32 is compressed it likewise places the disc spring under compression and it maintains the disk spring in a substantially uniform compressed high-speed cutting condition throughout the range of adjustment of the tool as determined by the extent of compression of the spring 32. The range of adjustment of the tool for any particular grinding operation is determined by the extent of compression of the coil spring 32 and the action of the adjustment limiting means above described. Consequently, in the use of my tool, I gain the cutting or grinding action, the stone cleaning feature and the non-chatter feature, of the high frequency spring, such as the spring 31, while at the same time gaining in the use of a spring like spring 32, a wide range of adjustment without stoppage of the tool during the grinding operation.

I claim:

1. A cylinder grinding tool comprising a body, abrasive carriers mounted in said body for expanding and contracting movements, abrasive elements carried by said carriers, and means for expanding said carriers which includes a pair of coacting springs, one having a high frequency and the other having a low frequency, and means disposed between said springs and said carriers for compressing said springs and adapted to be shifted by said springs when compressed to expand said carriers and hold said abrasive elements in abrading contact with the cylinder wall.
2. A cylinder grinding tool comprising a body, abrasive carriers mounted in said body for expanding and contacting movements, and means

for expanding said carriers which includes a pair of coacting springs having different frequencies, and means disposed between said springs and said carriers for compressing said springs and upon which said springs when compressed act to expand said carriers.

3. A cylinder grinding tool comprising a body, abrasive carriers mounted in said body for expanding and contracting movements, and means for expanding said carriers which includes a pair of springs of substantially equal load carrying capacity so arranged that one spring acts upon the other, said one spring having a lower frequency than the other spring, and means disposed between said springs and said carriers and adjustable to place said springs under compression and adapted to be moved by said springs when compressed to expand said carriers.

4. A cylinder grinding tool comprising a body, abrasive carriers mounted in said body for expanding and contracting movements, and means for expanding said carriers which includes a pair of springs of substantially equal load carrying capacity, one being capable of small deflection only for a given load and the other being capable of substantially greater deflection for said given load, the arrangement being such that one of said springs acts upon the other, and means disposed between said springs and carriers and adjustable to place said springs under compression and movable under the influence of said springs when compressed to expand said carriers.

5. A cylinder grinding tool comprising a body, abrasive carriers mounted in said body for expanding and contracting movements, abrasive elements carried by said carriers, and means for expanding said carriers which includes a pair of springs of substantially equal load carrying capacity, one of said springs having small deflection ability with a high frequency and the other having greater deflection ability with a low frequency, a member operably engaged with said carriers and shiftable to expand the latter, said member being adjustable to compress said springs, the arrangement being such that said high frequency spring acts upon said member through said low frequency spring to shift said member to expand said carriers and to hold the abrasive elements thereof in grinding contact with the cylinder wall to be ground.

6. A cylinder grinding tool comprising a body, abrasive carriers mounted in said body for expanding and contracting movements, and means for expanding said carriers which includes a shiftable device acting on said carriers to expand the latter, and means for automatically shifting said device in expanding direction which includes a compressible unit having one portion adapted to operate with a high frequency of vibration and a coacting part adapted to operate with a low frequency of vibration.

7. A cylinder grinding tool having a body, abrasive carriers mounted in said body for expansion and contraction movements, an expanding unit which includes a shiftable member, expanding elements on said shiftable member adapted to engage and expand said carriers as said member shifts, and compressible means cooperating with said shiftable member to shift the same and expand said carriers as the grinding operation progresses, said compressible means having one part capable of small deflection for a given load and another coacting part capable of greater deflection for said given load, said two parts having different frequencies of vibration. 75

8. A cylinder grinding tool having a body, abrasive carriers mounted in said body for expansion and contraction movements, an expanding unit which includes a shiftable member, expanding elements on said shiftable member adapted to engage and expand said carriers as said member shifts, and compressible means cooperating with said shiftable member to shift the same and expand said carriers as the grinding operation progresses, said compressible means having one part with a high frequency of vibration and another part with a low frequency of vibration.

9. A cylinder grinding tool having a body, abrasive carriers mounted in said body for expansion and contraction movements, an expanding unit which includes a shiftable member, expanding elements on said shiftable member adapted to engage and expand said carriers as said member shifts, and compressible means adapted to be compressed by adjustment of said shiftable member and acting on said shiftable member to shift the same and expand said carriers as the grinding operation progresses, said compressible means including a pair of springs, one capable of small deflection and a high frequency of vibration and the other capable of greater deflection and a lower frequency of vibration, said springs acting one directly upon the other and having substantially the same load carrying capacity.

10. A cylinder grinding tool having a body, abrasive carriers mounted in said body for expansion and contraction movements, an expanding unit which includes a shiftable member, expanding elements on said shiftable member adapted to engage and expand said carriers as said member shifts, and compressible means cooperating with said shiftable member to shift the same and expand said carriers as the grinding operation progresses, said compressible means including a pair of springs, one of which is a disk type spring having small deflection and a high frequency and the other of which is a coil spring having considerably greater deflection and a low frequency.

11. A cylinder grinding tool comprising a body, abrasive carriers mounted in said body for expansion and contraction movements, abrasive elements carried by said carriers and adapted to engage the cylinder wall to be ground, carrier expanding means including a stem member mounted for axial shift movement in said body, expanding elements on said stem member adapted to engage said carriers and expand the same as said stem member is shifted, and compressible means adapted to be compressed by said stem member for shifting said stem member and having one part with low deflection ability and another coacting part with high deflection ability.

12. A cylinder grinding tool comprising a body, abrasive carriers mounted in said body for expansion and contraction movements, abrasive elements carried by said carriers and adapted to engage the cylinder wall to be ground, carrier expanding means including a stem member mounted for axial shift movement in said body, expanding elements on said stem member adapted to engage said carriers and expand the same as said stem member is shifted, and compressible means adapted to be compressed by said stem member for shifting said stem member in tool expanding direction and having one part

with a high frequency of vibration and another coating part with a low frequency of vibration.

13. A cylinder grinding tool comprising a body, abrasive carriers mounted in said body for expansion and contraction movements, abrasive elements carried by said carriers and adapted to engage the cylinder wall to be ground, carrier expanding means including a stem member mounted for axial shift movement in said body, expanding elements on said stem member adapted to engage said carriers and expand the same as said stem member is shifted, and compressible means for shifting said stem member and having one part with a low deflection but high frequency of vibration characteristic and another part with a high deflection but low frequency of vibration characteristic, one of said parts acting on the other which in turn acts on said stem member to shift the latter.

14. A cylinder grinding tool comprising a body, a plurality of abrasive carriers mounted in said body for expansion movement, abrasive elements carried by said carriers and adapted to engage the cylinder wall to be ground, and means for automatically expanding said carriers which includes a member axially shiftable in said body, expanding elements carried by said member and engaging said carriers to expand the latter as said member is shifted axially, and means for shifting said member which includes a compressible unit of substantially uniform load carrying capacity throughout while having one part constructed to have a high frequency of vibration and another part constructed to have a low frequency of vibration.

15. A cylinder grinding tool comprising a body, a plurality of abrasive carriers mounted in said body for expansion movement, abrasive elements carried by said carriers and adapted to engage the cylinder wall to be ground, and means for automatically expanding said carriers which includes a rotatable threaded member shiftable axially of said body, nonrotatable expanding elements carried by said member and engaging said carriers to expand the latter as they are shifted axially, and means for shifting said member which includes a compressible unit confined between said member and said body, said unit being in part constructed for low deflection and a high frequency of vibration and in part for high deflection and a low frequency of vibration, said unit being compressed by rotation of said member with said abrasive elements engaged with the cylinder wall to be ground.

16. A cylinder grinding tool comprising a body, a plurality of abrasive carriers mounted in said body for expansion movement, abrasive elements carried by said carriers and adapted to engage the cylinder wall to be ground, and means for

automatically expanding said carriers which includes a rotatable threaded member shiftable axially of said body, nonrotatable expanding elements carried by said member and engaging said carriers to expand the latter as they are shifted axially, and means for shifting said member which includes a pair of springs confined between said member and said body, one of said springs having a low deflection and high frequency characteristic and the other having a high deflection and a low frequency characteristic, said springs acting directly on each other with one spring acting directly on said member.

17. A cylinder grinding tool comprising a body, abrasive carriers mounted in said body for expansion movement, abrasive elements carried by said carriers and adapted to engage the cylinder wall to be ground, carrier expanding means mounted in said body including a member shiftable axially to expand said carriers, a stop on one end of said member adapted to engage said body and limit shift movement of said member in carrier expanding direction, compressible spring means for automatically shifting said member in carrier expanding direction, said member being shiftable in a direction opposite its carrier expanding shift movement to compress said compressible means, said latter shift movement of said member moving said stop away from said body a predetermined distance to permit a predetermined shift movement of said member in carrier expanding direction to effect a predetermined carrier expansion.

18. A cylinder grinding tool comprising a body, abrasive carriers mounted in said body for expansion movement, abrasive elements carried by said carriers and adapted to engage the cylinder wall to be ground, carrier expanding means mounted in said body including a member shiftable axially to expand said carriers, a stop on one end of said member adapted to engage said body and limit shift movement of said member in carrier expanding direction, compressible spring means for automatically shifting said member in carrier expanding direction, said member being shiftable in a direction opposite its carrier expanding shift movement to compress said compressible means, said latter shift movement of said member moving said stop away from said body a predetermined distance to permit a predetermined shift movement of said member in carrier expanding direction to effect a predetermined carrier expansion, and calibrated indicator means carried by said member for determining the extent of shift movement of said member to compress said spring means and in turn the extent of permitted expansion of said carriers.

WALLACE F. MITCHELL.
